UNITED STATES PATENT OFFICE.

GUSTAV N. MEVES, OF DAVENPORT, IOWA.

OPERATING MECHANISM FOR WASHING AND LIKE MACHINES.

1,086,548.

Specification of Letters Patent.

Patented Feb. 10, 1914.

Application filed February 17, 1912. Serial No. 678,422.

To all whom it may concern:

Be it known that I, GUSTAV N. MEVES, a citizen of the United States, and a resident of Davenport, in the county of Scott and State of Iowa, have invented certain new and useful Improvements in Operating Mechanism for Washing and like Machines; and I do hereby declare that the following is a full, clear and exact description thereof, reference being had to the accompanying drawings, and to the characters of reference marked thereon, which form a part of this specification.

This invention relates to improvements in motor driven operating mechanisms for washing and like machines adaptable to such mechanisms as embody a main or primary operating or stirrer head shaft or element within the tub to which is imparted a rotary, reciprocatory motion through unidirectional motion of a motor driven element or shaft.

The invention relates also to an improved mechanism associated with the means for driving the main shaft or element for operating a secondary shaft or element, such as a roller shaft or shafts of a wringer mounted on the washing machine, the arrangement being such as to drive the secondary shaft in opposite directions and to afford means for connecting the motor to and disconnecting it from the primary and secondary shafts so that said shafts may be driven concurrently or independently of each other.

Among the objects of the invention are to improve and simplify power operative mechanisms of this character, and, further to provide means for operating from the secondary shaft a tertiary shaft, such as the roller shaft of a second wringer supported on a stand adjacent to the washing machine.

Other objects of the invention will appear from the following description, and the invention consists in the arrangement and combination of parts hereinafter described and more particularly pointed out in the appended claims.

In the drawings;—Figure 1 is a side elevation of a washing machine embodying my invention, with parts broken away. Fig. 2 is a rear elevation of the machine, with parts broken away. Fig. 3 is a top plan view of the machine. Fig. 4 is a detail section on the line 4—4 of Fig. 3. Fig. 5 is a horizontal section on the line 5—5 of Fig. 1. Fig.

6 is a detail of the motor driven operating shaft. Fig. 7 is a rear view of the machine, showing a wringer stand and extension, together with a second wringer supported on the stand, and means for driving the second wringer from the main wringer. Fig. 8 is a top plan view of the parts shown in Fig. 7.

Referring first to the construction shown in Figs. 1 to 6, inclusive, the tub 10 is provided with the usual swinging lid 11 and is supported on legs 12, which latter are connected by the horizontal braces 13. The stirrer head shaft 14 is rotatively mounted in the lid of the machine in a manner familiar in machines of this character and is provided at its upper end with a pinion 15. Said pinion 15 meshes with a second pinion 16 that is fixed to a rotative shaft 18 which is mounted in bearings 19, 19 formed on a frame plate 20 supported on the hinged portion of the tub top, or lid. The said shaft 18 is provided at its outer end with a pinion 22 that meshes with a pinion 23 fixed to a horizontal shaft 24 arranged at a right angle to the shaft 18. The shaft 24 is mounted in bearings 25, 25 which are carried by a frame plate 27 that is fixed to the non-rising portion 28 of the tub top.

The hinged portion of the tub top or lid is swingingly mounted on said shaft 24 through the medium of bearing members 29, 29 that are fixed to the standards 30 that rise from the frame plate 20 at the swinging margin of the hinged portion of the tub top. This construction is generally similar to that shown in my prior application for U. S. Letters Patent No. 657,473 filed October 30, 1911.

The other end of the shaft 24 is provided with a pinion 31 which meshes with a pinion 32 that is fixed to the upper end of an upright polygonal shaft 33 arranged at the side of the tub, with its upper cylindric end mounted in bearings 34 carried by the frame plate 27 and with its lower end mounted in a step bearing 35, as best shown in Fig. 1. Slidably mounted on the lower end of the upright shaft 33 is a cylindric member 37 which has a polygonal opening fitted on the shaft 33 to permit it to slide endwise on said shaft, but prevents it from rotating relatively to the shaft. Said sliding cylinder member is provided between its ends with a horizontal, arcuate rack 38 comprising a series of teeth which may be connected at their 110

outer ends by the curved bar 38'. Said rack is adapted to mesh with the relatively coarse teeth of a gear wheel 39 that is fixed to one end of a horizontal, motor driven shaft 40 which is mounted in bearing standards 41, 41, shown as made integral with and rising from a frame plate 42 which is supported on the brace members 13. The said shaft 40 is driven by a motor 45 by driving connection hereinafter described.

The sliding cylinder member 37 is provided at the sides of the rack teeth 38 with curved guide ribs or shoulders 46 shown in full lines in Fig. 1, and in dotted lines in Fig. 5. Said curved ribs extend from the top to the bottom of the cylinder and are connected at the upper and lower ends of the cylinder to constitute a continuous guide or track to coöperate with an extension 47 of the shaft 40; the said extension 47 projecting into the recessed portion of said cylinder surrounded by said curved guide ribs. The arrangement is such that when the gear wheel 39, which has a continuous unidirectional rotative movement, reaches the end of the rack 38, the engagement of said extension 47 with said curved guide ribs has the effect to hold the toothed wheel 39 engaged with the rack and to slide the cylinder 37 endwise on the shaft 33, so as to cause the said toothed wheel to pass from one side of the rack to the other, and thereby reverse the direction of rotation of the cylinder and its shaft 33 and the operating shaft geared thereto. In this manner the toothed wheel 39 is caused to mesh first with the upper side and then with the lower side of the rack 38 so that, through continuous, unidirectional rotation of the shaft 40, a rotary, reciprocatory motion is imparted to the cylinder, the shaft 33 and to the operating or dasher shaft 14. The said shaft 40 is driven from the motor 45 through the medium of a pinion 50 on the motor shaft 51, said pinion meshing with a gear wheel 52 which is fixed to a sleeve 54 that is loosely mounted on the shaft 40 and which has bearing on such shaft. Said sleeve 54 is held from endwise movement on the shaft 40 by means of an annular rib or collar 55 thereon which engages a notch formed in the upper end of a standard 56, as best shown in Figs. 1 and 5. The said sleeve 54 is normally loose on the shaft 40 and is adapted to be locked thereto so as to cause the shaft to rotate therewith by a suitable clutch device. Said clutch device, as herein shown, consists of a collar 58 that is slidably mounted on the shaft 40, and is held non-rotative thereon by a pin 59 on the shaft which extends through a slot in the collar. The collar is provided at one end with clutch teeth or jaws 60 adapted, by sliding movement of the collar, to be brought into engagement with corresponding clutch teeth or jaws 61 formed on the adjacent end

of the sleeve 54. The means herein shown for shifting said clutch to connect it to and disconnect it from the sleeve consist of a horizontal swinging shipping lever 63 that is pivoted at 64 to a bracket 65 attached to the bottom of the tub. The end of said shipping lever beyond its pivot is turned downwardly, as shown at 66, and the downturned portion is provided at its lower end with a bearing roller 68 that enters an annular groove 69 formed in any suitable manner on the periphery of the clutch collar. The other or free end of the shipping lever 63 extends to the right hand side of the machine and is formed with a hand piece 71. The said free end of the lever is adapted to be held in position to lock the clutch in either its open or its closed position by means of the segment 72 having the two notches to alternately receive the lever, said segment being attached to the bottom of the tub.

73 designates a wringer, of any usual or preferred construction, that is mounted on the wringer board 76 supported at the rear of the machine, and is provided with the usual rollers having geared shafts. The shaft 77 of the lower roll is operatively connected to the sleeve 54 of the shaft 40, whereby the wringer is operated from the motor, through following gearing. The said sleeve 54 is provided near its outer end with a double faced gear 80, having opposing beveled gear faces. It is splined or otherwise non-rotatively secured to the sleeve 54 to rotate therewith, but is permitted to slide endwise thereof by the spline 80'.

81 designates an upright shaft arranged at the rear and to one side of the tub and is rotatively mounted at its lower end in a bearing 82 carried by an overhanging arm 105 on the standard 41. The shaft is rotatively mounted at its upper end in a suitable bearing 83 that is carried by the outer end of the frame plate 27. The said shaft 81 is provided at its upper end with a pinion 85 which meshes with a beveled gear wheel 86 carried by the shaft of the lower wringer roll. Said shaft 81 is provided at its lower end with a beveled pinion 88 which extends into the space between the opposing beveled gear faces of the double gear 80, as best shown in Figs. 1 and 5. By shifting said double gear endwise on the shaft, the beveled pinion 88 may be brought into mesh with either of the gear faces of the double gear, 110 or be made to occupy a neutral position relative to said gear faces. By this construction the shaft 81 and the wringer roll shaft geared thereto may be rotated in either direction, or may be disconnected from power. 120 The double gear may be thus shifted on the sleeve by devices made as follows: 92 designates a shipping lever that is pivoted at 93 to a bracket 94 which is attached to one of the tub legs. One end of said shipping 130

lever 92 is provided with a bearing roller 95 that extends into a groove 96 of the double gear. The other end of the shipping lever extends to the right hand side of the machine, near the rear thereof, and is attached to the lower end of a vertically swinging operating lever 97 that is pivoted at 98 to a bracket 99 which is fixed to the side of the tub. The upper end of the operating lever is formed with a hand piece 100, and said upper end of the operating lever is adapted to be held in a fixed position, to hold the double gear in either of its three positions of adjustment, by engagement with one of the three notches 101, of a bracket 102 attached to and extending laterally from the side of the tub, near the top thereof.

If it be desired to operate the main operating or dasher shaft by hand power at a time when motor power is not available, the shaft 18 may be extended beyond its bearings 19 and provided with a socket 105 to receive a hand lever, so that the machine may be operated in the ordinary manner of a lever machine. In lieu of the motor 45, which may be an electric motor, I may provide the shaft 51 with a pulley through which power from an extraneous source, as from a gas engine, may be transmitted to operate said shaft.

In Figs. 7 and 8 I have shown an arrangement whereby the main wringer 75 may be operatively connected to a second wringer 110 that is supported on a combined wringer and tub stand 111 arranged at the side of the washing machine tub; said wringer stand being constructed to constitute a support for two tubs 112 and 113, one at each side of the wringer 110. The rearmost tub 112 may be supported on a truck 115, the wheels of which are adapted to be supported by and travel on the rails 116 of the wringer stand extension that extends laterally from the wringer stand to a position in rear of the main wringer, whereby said tub 112 may be shifted either to the position shown in full lines in Fig. 8 or to the position indicated in the dotted lines therein.

The second or auxiliary wringer 110 is arranged with its lower roll shaft in general axial alinement with the shaft of the lower roll of the main wringer, and may be connected thereto, as by the coupling 119 shown in the Figs. 7 and 8, and made of any suitable construction. The said shaft of the lower roll of the main wringer is provided with the right and left hand screw threads 120, 121, to the former of which the coupling is adapted to be screwed and to the latter of which is applied a lock nut 122 to lock the coupling 119 in place. Said coupling may be attached to the lower roll shaft of the wringer 110 in a similar or any other suitable manner.

The various intermeshing gears are housed

by suitable shaped gear casings, the outlines of which are shown in Figs. 1, 2, 3, 7 and 8 and need not be further described.

It will be understood that the structural details of the various mechanisms may be varied within the spirit and scope of the invention, and that the invention is not limited to such details except as hereinafter specifically claimed, or as imposed by the prior art.

I claim as my invention:—

1. Operating mechanism for washing and like machines comprising, in combination with a body, an operating shaft mounted therein and capable of rotary, reciprocatory motion, a motor driven shaft beneath the body with driving means for rotating it in one direction, an upright shaft at the side of the body, gearing connecting the upper end of said shaft to said operating shaft and operative connections between the motor driven shaft and the lower end of the upright shaft, having means to translate the continuous rotary motion of the motor driven shaft into rotary, reciprocatory motion of the upright shaft.

2. Operating mechanism for washing and like machines comprising, in combination with a body, an operating shaft mounted therein and capable of rotary, reciprocatory motion, a motor driven shaft beneath the body with driving means for rotating it in one direction, an upright shaft at the side of the body, gearing connecting the upper end of the said shaft to said operating shaft, a cylinder on said upright shaft non-rotatively connected thereto and slideable thereon, a rack on said cylinder, a toothed gear on the motor driven shaft meshing with said rack and interacting with guiding parts on the cylinder and said motor driven shaft to hold the toothed gear in mesh with the rack and to guide it to engage it first with one side and then with the other of said rack.

3. Operating mechanism for washing and like machines comprising, in combination with a body, an operating shaft mounted therein and capable of rotary, reciprocatory motion, a motor driven shaft beneath the body with driving means for rotating it in one direction, an upright shaft at the side of the body, gearing connecting the upper end of said shaft to said operating shaft, a cylinder on said upright shaft non-rotatively connected thereto and slideable thereon, an arcuate rack extending from and normal to the plane of said cylinder, a toothed gear on said motor driven shaft meshing with said rack, said cylinder having curved guides and an extension on the motor driven shaft beyond said pinion for engagement with said curved guides.

4. Operating mechanism for washing and like machines comprising, in combination

with a body, an operating shaft mounted therein and capable of rotary, reciprocatory motion, a motor driven shaft beneath the body with driving means for rotating it in 5 one direction, an upright shaft at the side of the body, a horizontal shaft geared to the upper end of the upright shaft, a second horizontal shaft geared to the first horizontal shaft and to the operating shaft, and 10 an operative connection between the motor driven shaft and the lower end of the upright shaft, having means to translate the continuous rotary motion of the former shaft into rotary, reciprocatory motion of 15 the latter shaft.

5. Operating mechanism for washing and like machines comprising, in combination with a body, a swinging member hinged to said body, an operating shaft mounted 20 therein and capable of rotary, reciprocatory

motion, a motor driven shaft beneath the body with driving means for rotating it in one direction, a horizontal shaft geared to the upper end of the upright shaft, gearing connecting said horizontal shaft with said 25 operating shaft, bearings for said horizontal shaft mounted on a fixed part of the body, and hinge lugs for the swinging member mounted on said horizontal shaft, whereby the latter shaft constitutes the 30 hinged pivot for the swinging member.

In testimony, that I claim the foregoing as my invention I affix my signature in the presence of two witnesses, this 12th day of February, A. D. 1912.

GUSTAV N. MEVES.
